(57) **CLAIM**

The ornamental design for a rear tractor screen assembly as shown and described.

DESCRIPTION

FIG. 1 is an isometric view of rear tractor screen assembly showing my new design;

FIG. 2 is a front elevational view thereof of FIG. 1;

FIG. 3 is a rear elevational view thereof of FIG. 1;

FIG. 4 is a right elevational view thereof of FIG. 1;

FIG. 5 is a left side elevational view thereof of FIG. 1;

FIG. 6 is a top plan view thereof of FIG. 1;

FIG. 7 is a bottom plan view of thereof of FIG. 1; and,

FIG. 8 is a perspective view of a rear tractor screen assembly shown in a state of use.

The broken lines are included for the purpose of illustrating environment and form no part of the claimed design.
